UNITED STATES PATENT OFFICE.

JAMES EDWIN HENDERSON, OF DENTON, TEXAS.

DESIGN FOR AN OIL-BURNER.

SPECIFICATION forming part of Design No. 35,380, dated December 3, 1901.

Application filed October 26, 1901. Serial No. 80,155. Term of patent 14 years.

To all whom it may concern:

Be it known that I, JAMES EDWIN HENDERSON, a citizen of the United States, residing at Denton, in the county of Denton and State of Texas, have invented and produced a new and original Design for an Oil-Burner, of which the following is a specification.

This invention relates to a new and original design for an oil-burner, and the essential features reside in the design as illustrated in the accompanying drawings, wherein—

Figure 1 is a perspective view of a burner embodying the features of the design. Fig. 2 is a transverse vertical section of the same.

The design is characterized by a trough-like lower member 1, having a lower convex side 2 and an upper concave cavity 3, the one end 4 of said member being rounded. Rising

from the opposite end of the member 1 is a projection 5, from which extends a hollow cylindrical member 6, disposed centrally over the member 1 below and approximately of the same length as the latter member. Extending upwardly from the member 6 are a series of projections 7.

Having thus described the invention, what is claimed as new is—

The design for an oil-burner, as herein shown and described.

In testimony that I claim the foregoing as my own I have hereto affixed my signature in the presence of two witnesses.

JAMES EDWIN HENDERSON.
